UNITED STATES PATENT OFFICE.

FRANK O. MELIN, OF COUNCIL BLUFFS, IOWA.

SAFETY DEVICE FOR OIL-BURNERS.

1,237,937.

Specification of Letters Patent. Patented Aug. 21, 1917.

Application filed December 18, 1916. Serial No. 137,675.

To all whom it may concern:

Be it known that I, FRANK O. MELIN, a citizen of the United States, residing at Council Bluffs, in the county of Pottawattamie and State of Iowa, have invented certain new and useful Improvements in Safety Devices for Oil-Burners, of which the following is a specification.

This invention relates to a safety device 10 for use in connection with gas generators where liquid fuel is employed, and has for its principal object to provide means which will be operative to automatically prevent a flow of the liquid fuel in instances when,

15 from accident or otherwise, the gas ceases to burn, the construction to be of few and simple parts, so that durability may be attained and manufacture will be economical. In the combustion of gas for heating purposes when oil is used for fuel, the liquid supply to the burner is usually controlled 20 by a valve which, in residences, is usually in an exposed position, and through inadvertence the valve may become injured or dis-

25 arranged to permit such an increased flow of oil that it will not be vaporized; also by action of air drafts, the burning of the gas may at any time be terminated, with the result that the flow of oil will continue to 30 thereby endanger the premises. By use of the herein described device, the flow of oil will cease if the oil is not vaporized or if ignition ceases.

The invention consists of the novel construction, combination and arrangement of parts as described herein and claimed, and as illustrated in the accompanying drawing, wherein:—

Figure 1 is a view of the device in side 40 elevation, applied to an oil burner, parts being in section. Figs. 2 and 3 show enlarged details. Fig. 2 is a view in longitudinal section through a valve employed, the gravity-cup or receptacle being partly 45 broken away. Fig. 3 is a broken away view showing a part of the overflow pipe, a ball valve and its connections also being shown for normally preventing a movement of air therethrough to the burner.

Referring now to the drawing, numeral 4 indicates an oil burner or priming pan similar to those generally used in connection with a furnace 5, the air for combustion being supplied by means of the tubular casting 5 so that the intake for air to the burner will be disposed above the convexed part

7 of the priming pan, for obtaining the best results in the vaporization of the oil, the conducting pipe for oil to the priming pan being indicated at 8.

In order that the supply of oil will cease, should combustion cease by inadvertence or otherwise, a valve 9 is provided which has a stem 10 with a tapered terminal. Upon this valve stem, near its upper end, is 60 mounted a washer 11, and a spiral spring 12 is disposed to circumscribe the stem between the washer 11 and a second washer 13, which is disposed on the packing nut 14.

The seat of the valve is indicated at 15. 70 Numeral 16 indicates a nut which is threaded on the upper end of the valve stem, and it will be understood that, as described, the valve will normally remain on its seat to prevent any flow of oil to the priming pan.

Numeral 17 indicates a clip which is mounted on the upper part of the valve-seat casting, and numerals 18, 19 and 20 indicate links which may be of any suitable length or proportion depending upon the 80 length of the valve stem. These links provide a flexible latch, link 19 being pivotally connected at its ends with the respective links 18 and 20, as indicated at *a* and *b*. The link 18 is pivotally mounted upon one end of 85 the clip, as indicated at *c* and link 20 is provided with a notch 21. At 22 is indicated a catch which is pivotally mounted near its inner end upon the end of the clip, as indicated at 23, said catch having an arm 90 *d* upon which is dependingly supported a re-

centacle 24. As thus described, the flexible latch may be so arranged that its link 19 will be disposed substantially at right angles to the 95 valve stem, the links 18 and 20 being disposed substantially parallel with said stem, the lower end of link 20 engaging in a slot *e* which is formed in the clip; and it will be understood that when the parts are disposed 100 as shown in the drawing, the spring 12 will be contracted and may be maintained in a compressed condition on account of the engagement of the catch in the notch of link 20, and that the arm *d* may be swung downwardly if an adequate force is applied thereto, in a manner to cause a release of the link 19 from the valve stem.

At 25 is indicated an overflow pipe having an intake *f* at its upper end in communication with the upper part of the priming pan, and having its discharge port *g* dis-

posed above the receptacle 24. To secure the best results, the vaporization of oil and combustion should occur at the dome 7 of the priming pan, and on account of the heated metallic parts, oil is vaporized as soon as it enters the priming pan or substantially so. By use of a needle valve (not shown) the supply of oil which enters the pan, during combustion, may be uniform and limited in quantity. It will be appreciated however that if, from sudden drafts of air or from other causes, combustion should cease, the resulting overflow and flooding of the premises with oil might cause damage to property or endanger property to loss by fire. Also, in some instances, from a lack of skill in management, the flow provided to the priming pan may be so great that the oil will not be vaporized, which also will result in an overflow.

In the operation of the device it will be seen that, if there is an undue flow of oil, it may partly fill the priming pan, but before the pan is filled with the oil it will be conducted to the receptacle 24, which, on account of the resulting additional weight of oil, will swing downwardly, and the catch 22 thereupon will be released. The release of the catch will permit retraction of the spring 12 which results in an immediate closure of the valve 9, to prevent any additional flow of oil through the supply pipe 8.

Since air should be delivered immediately above the dome 7, to aid combustion, means are provided to prevent air from passing through the pipe 25 as a counter draft, said means consisting of a ball valve 26 disposed between the intake and discharge ports of said pipe. Also in the operation of burning the gas, decomposed carbon will form to a greater or less extent in the priming pan and will enter the pipe 25, and normally, will be moved downward to the ball valve, and therefore the valve housing for this valve is provided with the short tubes 27 and 28, these being disposed in vertical alignment,

the tube 27 of lesser diameter providing the valve seat and the tube 28, preferably, having a greater diameter than the ball valve, so that said valve may be removed. By the construction as described, the interior of the tubes may be conveniently cleaned whenever required, their screw-caps *a* being removed for this purpose.

A recess *m* is formed in the link 19 midway between its ends, so that the end of the valve stem 10 may make suitable engagement with said link and will not become detached therefrom, when the spring 12 is compressed. By adjusting the nut 16 longitudinally of the valve stem, the spring may have a greater or lesser degree of compression, and this is a very useful feature since the engagement of the catches with the latches may not be uniform, and the weight of receptacles 24 or lengths of arms *b* of the catches, when manufactured or used, may not be uniform.

What I claim and desire to secure by Letters Patent is,--

A safety device for the purpose described, comprising, in combination with the oil supply pipe of the priming pan, a valve provided with a stem and disposed in the supply pipe, a spring mounted on the stem, a flexible latch engaging the stem for compressing the spring, a catch provided with a receptacle and arranged for engaging with the latch to normally maintain the valve detached from its seat, a conducting pipe having an intake in communication with the priming pan and having its discharge port disposed adjacent to and above said receptacle, and a check valve between the intake and discharge ports of the conducting pipe.

In testimony whereof, I have affixed my signature in presence of two witnesses.

FRANK O. MELIN.
